(57) **CLAIM**

The ornamental design for a grip device for a vehicle wheel, as shown and described.

DESCRIPTION

FIG. 1 is a perspective view of the grip device for a vehicle wheel;

FIG. 2 is a front view of the grip device for a vehicle wheel;
FIG. 3 is a rear view of the grip device for a vehicle wheel;
FIG. 4 is a left view of the grip device for a vehicle wheel;
FIG. 5 is a right view of the grip device for a vehicle wheel;
FIG. 6 is a underside view of the grip device for a vehicle wheel;

FIG. 7 is a top view of the grip device for a vehicle wheel;
FIG. 8 is a perspective view of the grip device for a vehicle wheel;

FIG. 9 is a front view of the grip device for a vehicle wheel;
FIG. 10 is a rear view of the grip device for a vehicle wheel;
FIG. 11 is a left view of the grip device for a vehicle wheel;
FIG. 12 is a right view of the grip device for a vehicle wheel;
FIG. 13 is a underside view of the grip device for a vehicle wheel; and,

FIG. 14 is a top view of the grip device for a vehicle wheel.

1 Claim, 14 Drawing Sheets
